Primary Examiner — Holly E Thurman*Assistant Examiner* — Altaira J Swangin(74) *Attorney, Agent, or Firm* — McClure, Qualey & Rodack, LLP(57) **CLAIM**

The ornamental design for a network storage device, as shown and described.

DESCRIPTION

FIG. 1 is a front top right perspective view of a network storage device, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear, left and bottom perspective view thereof;

FIG. 9 is a partial enlarged view of the area '9' designated by the dash-dot region in FIG. 2; and,

FIG. 10 is a partial enlarged view of the area '10' designated by the dash-dot region in FIG. 3.

The even-dash broken lines in the drawings represent portions of the network storage device and form no part of the

(Continued)

claimed design, and the dash-dot broken lines in FIGS. 2-3 and 9-10 represent the bounds of the enlarged detail views and form no part thereof.

1 Claim, 9 Drawing Sheets
